HARRY KERSHAW INVENTOR

By John W. Tolman Jr.
Attorney

UNITED STATES PATENT OFFICE.

HARRY KERSHAW, OF MANCHESTER, ENGLAND.

GRINDING ATTACHMENT FOR LATHES.

1,251,047.

Specification of Letters Patent. Patented Dec. 25, 1917.

Application filed April 3, 1917. Serial No. 159,598.

To all whom it may concern:

Be it known that I, HARRY KERSHAW, a subject of the King of Great Britain and Ireland, and resident of Manchester, county 5 of Lancashire, England, have invented a certain new and useful Improvement in Grinding Attachments for Lathes, for which I have obtained a patent in Great Britain, No. 100,619, dated March 22nd, 1916, of

which the following is a specification.

This invention relates to internal grinding, milling, cutting and like machines of the type in which the grinding wheel or cutter is carried upon a rotary spindle which is 15 eccentrically or radially adjustable for the purpose of feeding the grinding wheel to the internal surface of the cylinder or other work to be machined, and to the type in which the grinder or mill or attachment 20 comprises a slow-moving member consisting of two parts secured together in eccentric relation to one another but moving as one, a fast-moving member rotatably mounted on said slow-moving member, means for 25 varying the eccentricity of the two-part slow-moving member and means for driving said slow and fast-moving members independently of one another.

The present invention consists in certain 30 novel combinations and arrangements of parts as hereinafter described and pointed out in the appended claims.

The invention, which is hereinafter described and illustrated as applied to the 35 nose of a lathe mandrel, is equally applicable for use with drilling, milling and other machine tools without any changes other than a change in the speed of rotation and the substitution of a cutter.

40 The invention is illustrated by the accompanying sheets of drawings, in which:—

Figure 1 is a longitudinal sectional view of the grinder or mill mounted on the nose of a lathe.

45 Fig. 2 is a section taken on line α , α of Fig. 1.

Fig. 3 is a section taken on line y , y of Fig. 1.

Fig. 4 is a fragmentary view showing the 50 means for effecting the fine adjustment of the cut or set, viz.—the eccentricity of the mandrel.

Fig. 5 is a view of a locking ring herein-after referred to.

55 Figs. 6 and 7 are detail views of a spring cap hereinafter referred to, Fig. 7 being a

section on line z , z of said Fig. 6, which is a side view of said cap.

Figs. 8 and 9 are views illustrative of an alternative form of drive connection between nose or back member and front or mandrel member.

Fig. 10 is a view showing an alternative arrangement for driving grinding wheel sleeve.

Fig. 11 is a diagrammatic view showing how such sleeve is driven from countershaft.

Fig. 12 is a longitudinal view partly in section of a modified arrangement of grinder or mill shown in Fig. 1; and,

Fig. 13 is a part plan view thereof showing a detail hereinafter referred to.

Like letters of reference indicate corresponding parts in the several figures.

Referring to the accompanying drawings, 75 it will be observed that a designates the face plate member, b the lathe spindle, c the base of the adjustable mandrel member, d the post or mandrel of the latter, and e —Figs. 1 and 5—a split locking ring, one-half of which grips the lathe spindle b , while the other half engages the end of the hub a' of the face plate member a . This split ring member e locks the face plate element to the lathe spindle to prevent the entire grinder assembly from flying off during its operation. With this arrangement, 80 it will be clear that the present invention essentially comprises an interior slow-moving element consisting of the face plate member 90 and mandrel member, and an external fast-moving element which acts as a casing for the slow-moving element and carries the grinder wheel or equivalent element. This exterior fast-moving casing element consists 95 of a flanged pulley member and a flanged sleeve member which coöperate to house the eccentric connection between the two main parts of the slow-moving member, as will hereinafter move fully appear.

The front and rear members c and a are secured together in eccentric relation to one another, as shown in Figs. 2 and 3, by means of two studs f , f' , which studs f , f' are carried by the flange a^2 of the face plate member a and extend through the flange c' of the front member c . Of these studs, the stud f is a master stud and serves as a pivot on which the base c of the mandrel member can swing, while the other stud f' passes 105 through a radial slot c^2 —Figs. 1 and 3—in the flange c' of the said base c , said studs 110

f, f' being provided with nuts *f^x* which lock the flanges *a², c'* in place after having been set over on a cut, said nuts being slackened or tightened by a box-key inserted through an accommodation hole in the flange *g'* of the fast-moving sleeve *g²*. To compensate for loss of weight due to the removal of metal from the flange *g'* in drilling the hole *g*, a spring cap *h* is pushed into said hole—Figs. 1 and 2—said cap, which is provided, as shown in Figs. 6 and 7, with a split ring *h'* like a piston ring and will only move if pulled, being of the same weight as the metal removed to form the hole, retaining the balance.

i is a pulley loosely mounted on the hub *a'* of the face plate element and driven from a countershaft (not shown) and at grinding wheel speed, said pulley *i* having a flange *i'* on which is mounted a roller *i²* which takes in and reciprocates in a slot *g³* in the flange *g'* of the fast-moving sleeve *g²* for the drive from flange *i* to flange *g'*, or instead of a roller, a square block may be employed if desired.

In the above construction, as also in the hereinafter described constructions, there is provided, as and where required (but not shown in the drawings), ball bearings between the fast-moving member and the slow-moving member, especially at the end carrying the adapter and the end of the spindle of the slow-moving member.

As an alternative way of drive between the flanges *i'* and *g'*, a link *j*—Figs. 8 and 9—may be employed, said link *j*, which is pivotally mounted on studs *j', j²* on the flanges, oscillating with the opposing movements of said flanges. *d'* is a bushing pushed 40 into the sleeve *g²*, said bushing *d'* having a running fit on the diminished end *d²* of the mandrel *d* and fitting up against the shoulder *d³* thereof. The bushing *d'* is held in position by means of a grub screw *d⁴* which comes under the adapter *k* which carries the grinding wheel *k'*, and the sleeve *g²* is locked on by means of the nut *d⁵* engaging the screwed portion of the diminished end of the mandrel *d*, keeping the fast-moving flanged sleeve *g²* in position.

The fine adjustment of cut or set, viz:—the eccentricity of the mandrel carrying the fast-moving sleeve is effected by means of the device shown in Figs. 1 and 3. This device consists of a fine threaded screw *m* fitted into and across the back of the slow-moving flange *c'*, and screwing through a block *m'* slidably mounted in a recess *m²* in said slow-moving flange *c'*, said block *m'* being provided with jaws *m³* which embrace the stud *f'* carried by the flange *a²* of the back slow-moving member *a*. This screw *m* when turned by a key passed through the hole or slot *g⁴* in the fast-moving flange *g'* shifts the block *m'* along the recess *m²*, and

by the engagement of the jaws *m³* with the stud *f'* which extends through the radial slot *c²* in the slow-moving flange *c'* causes said slow-moving flange and mandrel *d* to be thrown over on the pivot *f* ever so little 70 or the full range as required, the jawed block *m* engaging the stud *f'* with clearance for the radial movement.

For the still finer adjustment of cut or set, viz:—the eccentricity of the mandrel carrying the fast-moving sleeve, the hole or slot *g⁴* for the passage of the key by which the micrometer screw *m* is turned, is made oval for the reception—see Fig. 4—of the over shaped boss *n* of a conical and removable sleeve *n'* in which is rotatably mounted the key proper *n²*, the arrangement being such that when the boss *n* of the sleeve *n'* is in position, the key *n²* can be turned without the sleeve *n'* turning, and as said sleeve *n'* is graduated on its surface at *n³*, and said key *n²* provided in its length with an index line or pointer *n⁴*, one is enabled, given the pitch of the micrometer screw *m*, to effect a much finer adjustment or cut or set.

In the modified arrangement shown in Figs. 10 and 11, the fast-moving member or sleeve *g²* is driven from in front of the slow-moving flanges *a², c'* by means of a pulley 1 running on the mandrel *d* of the base *c* of the slow-moving member, said pulley 1 engaging the fast-moving flange 2 by means of studs 3 to prevent the pull of the belt affecting the grinding wheel, slackening and tightening of said belt 4 caused by the orbital movement being taken up by means of a rocking countershaft 5, as shown in Fig. 11.

In the modified arrangement of grinder or mill shown in Figs. 12 and 13, the front part *g^x* of the fast-moving sleeved member *g²* is made box-shape so as to extend backward to inclose the abutting portions or flanged ends *a², c'* of the two part slow-moving member *a, c*, and such box is closed by means of a plate *P* detachably mounted in the mouth of said box, a suitably disposed slot *g⁵* in said plate *P* allowing of the passage of a pin *i²* on the flange *i'* of the fast-moving pulley *i* to drive said box-ended fast-moving sleeved member *g²*, said pulley *i* being separable from the beforementioned detachable plate *P*.

Instead of using the accommodation hole *h'* and spring cap *h* in the front part *g^x* of the fast-moving member to allow of the bolts *f^{*}* holding the two eccentrically disposed slow-moving members together to be slackened or tightened, there may be employed in lieu thereof, and as shown in Fig. 13, a long peripheral slot *h²* formed in the wall of the box-ended front part of the fast-moving sleeved member *g²*, said slot, which is normally closed by means of a slide or shroud *h³*, allowing of the insertion of a flat spanner to slacken or tighten the bolts *f^{*}*.

Further, in the wall of the box-end of the fast-moving member there is provided the oval hole g^4 for the reception of the oval boss of the sleeve carrying key as before described with reference to Fig. 4.

Having now described my invention, what I claim as new and desire to secure by Letters Patent of the United States is:—

1. A grinding attachment for lathes including in combination with the lathe spindle, a slow-moving member including a face plate having a hub fitted to said spindle and a mandrel member having a base provided with a recess on its inner face communicating with an arcuate slot opening at its outer face, bolts for clamping said face plate and base of the mandrel together, one of said bolts constituting a pivot for the mandrel member and the other of said bolts projecting through the recess and arcuate slot of said base, a yoke piece mounted in the recess of the base of the mandrel member and engaging the shank of the bolt passing through the same and said slot for adjusting the mandrel member eccentrically with the face plate, a screw engaging with said yoke-piece and accessible from the periphery of the base of the mandrel member, a fast-moving member including a sleeve rotatably mounted on said mandrel member carrying a tool and a pulley element.

2. A grinding attachment for lathes, including in combination with the lathe spindle, a slow-moving member consisting of a face plate having a hub to fit on the lathe spindle, a mandrel member provided with a base eccentrically pivoted to the face plate, a fast-moving member consisting of a flanged pulley rotatably mounted on the hub of the said face plate member, and a sleeve pro-

vided with a flange having a slot rotatably mounted on the said mandrel, said flanged pulley and flanged sleeve providing a housing for the eccentrically connected parts of the slow-moving member, an adapter mounted on said sleeve, a grinding wheel carried by said adapter, a roller carried by the flanged pulley for engaging and reciprocating in the slot in the flange of the fast-moving sleeve, means for varying the eccentricity of the members of the slow-moving part, and means for clamping the slow-moving member to the lathe spindle.

3. A grinding attachment for lathes including in combination with the lathe spindle, an interior slow-moving element consisting of a face plate member and a mandrel member eccentrically connected, and an external fast-moving element consisting of a pulley member and a sleeve member carrying a grinder wheel, said members of the latter element having portions coöoperating to provide a housing for the eccentric connection of the members of the interior element and also coupled with each other, and means located at the end of the mandrel member and mandrel casing member for locking the fast moving element on the slow-moving element, and means for engaging a portion of the pulley member of the fast-moving element and the lathe spindle to lock the entire assembly to the latter.

In testimony whereof I have affixed my signature hereto, this 27 day of February, 1917.

HARRY KERSHAW.
